UNITED STATES PATENT OFFICE.

JOHN A. WHITTAKER, OF DETROIT, MICHIGAN.

TIE FOR ANCHORING FLOOR SLEEPERS.

Application filed November 24, 1923. Serial No. 678,702.

To all whom it may concern:

Be it known that I, JOHN A. WHITTAKER, citizen of the United States, residing at Detroit, county of Wayne, State of Michigan, have invented a certain new and useful Improvement in Ties for Anchoring Floor Sleepers, and declare the following to be a full, clear, and exact description of the same, such as will enable others skilled in the art to which it pertains to make and use the same, reference being had to the accompanying drawings, which form a part of this specification.

My invention relates to an improvement in ties for anchoring floor sleepers to a concrete bed or slab.

In laying wooden flooring upon a concrete base it is essential that the floor sleepers,—to which the wood flooring is nailed,—should be securely anchored against displacement upon the concrete bed or base. Heretofore it has been customary to insert a plurality of metal strips in the concrete bed or base while the latter is in a plastic condition,—the strips being embedded so that they may project above the plane of the bed for attachment to the floor sleepers.

This device has been found objectionable because of the difficulty in inserting and "lining up" the strips in the concrete bed, and furthermore it requires the workman to walk over the plastic surface of the concrete bed, first to embed the strips in the concrete and then to nail them to the sleepers laid upon the slab;—and as the surface of the concrete slab may be more or less uneven it is difficult to properly align the strips so that their upper edges will be on an even plane.

To overcome this and other objections is the purpose of this present invention which consists of a device constructed of sheet metal in the form of a yoke with corrugated walls extending downwardly and projecting laterally from each side of the sleeper to provide bonding means whereby it may not become separated from the concrete filling, which is poured between the floor sleepers embedding the anchor plates therein:—the concrete filling being substantially on a plane with the top of the sleepers when properly filled.

One of the objects of the present invention is to provide a simple and very inexpensive device to manufacture which is adapted to

afford a sufficient bond to insure the anchor plate being securely held by the concrete filling.

A further object of the invention is to provide a device which is not apt to be tipped when lodged in the sleeper through workmen walking over the surface or due to the concrete filling itself when poured between the sleepers causing the anchors to tilt by the weight of the filling if filled unequally or because one side of the sleeper receives the filling before the other;—the narrow edge of the device not offering sufficient surface for the concrete filling to lodge upon, whereby it may be tipped unevenly in the sleeper.

With the foregoing and other objects in view which will appear as the description proceeds the invention further resides in the details of construction hereinafter described and claimed it being understood that changes may be made in the precise embodiment of the invention herein disclosed without departing from the spirit of the same.

In the drawings accompanying this specification:

Figure 1 is a perspective view of the device showing its corrugated side walls provided with slots through which the concrete filling may pass to increase the bonding effect.

Figure 2 is a vertical cross-sectional view through a plurality of sleepers fitted with anchor or tie plates as shown in Figure 1, the slab between the sleepers being covered with concrete substantially level with the top of the sleepers, upon which is secured a wooden flooring.

Figure 3 is a fragmentary plan view of a concrete bed, showing a pair of sleepers with the anchor plates in position.

Figure 4 is a perspective view of a modification in which the corrugated side walls of the anchor plate are imperforated in counterdistinction to the form shown in Figure 1.

Referring now to the letters of reference placed upon the drawings:

A, denotes a concrete bed or slab as usually prepared to receive the wooden floor sleepers B, placed thereon in spaced relation to each other.

C, indicates a sleeper tie, or anchor plate constructed of sheet metal, its central bridge portion C^a being adapted to enter a transverse kerf cut in the top of the sleeper.

The depending portions C^b of the anchor plate adjacent the side walls of the sleeper are corrugated as shown at C^c to increase the bonding surface exposed to the concrete filling D , lodged between the sleepers.

The concrete filling D is poured between the sleepers upon the concrete slab beneath, embedding the anchor plates suspended in the kerf cut in the sleepers.

10 E designates a wood flooring secured to the sleepers B.

C^f represents slots formed in the side walls of the anchor plates through which the concrete filling may pass to increase the bonding surface.

When embedding the tie in the floor sleepers it is not necessary to cut a kerf of a depth equal to the width of the bridge connecting the depending side portions of the 20 anchor plate together, as all that is required is to make the cut sufficiently deep so that the edge of the tie may be embedded that it may be driven flush with the top of the floor sleeper by a blow of the hammer.

25 After filling the spaces between the sleeper with concrete the flooring may be nailed to the sleepers.

It will be noted that in the use of this device it is not necessary for a workman to 30 walk over the concrete slab to nail the ties to the sleepers, nor are the anchor plates apt to be disturbed by workmen walking over the concrete, or before the concrete filling is poured between the sleepers as only a 35 narrow edge is presented which the workman is apt to take pains to avoid especially as the upper surface is inclined away from the connecting bridge, thereby making it more difficult to walk upon.

Having thus described my invention what 40 I claim is:

1. A device for anchoring floor sleepers to a concrete slab, comprising a U-shaped sheet metal member including spaced legs and a connecting bight portion, the device 45 adapted to straddle a floor sleeper with the bight portion lodged edgewise in a kerf cut in the sleeper with the legs projecting laterally from the sides of the sleeper in a line with said kerf, the legs being corrugated 50 and each leg having a slot therein.

2. A device for anchoring floor sleepers to a concrete slab, comprising a U-shaped sheet metal member including spaced legs and a connecting bight portion, the device 55 adapted to straddle a floor sleeper with the bight portion lodged edgewise in a kerf cut in the sleeper with the legs projecting laterally from the sides of the sleeper in a line with said kerf, the legs being corrugated. 60

3. A device for anchoring floor sleepers to a concrete slab, comprising a U-shaped sheet metal member including spaced legs and a connecting bight portion, the legs and bight portion being disposed in the same 65 plane and the device adapted to straddle the floor sleeper with the bight portion lodged edgewise in a kerf cut in the sleeper with the legs projecting laterally in alinement with the ends of the bight portion and in 70 line with the said kerf.

In testimony whereof, I sign this specification in the presence of two witnesses.

JOHN A. WHITTAKER.
